ATTORNEY

WITNESS:

UNITED STATES PATENT OFFICE.

ARTHUR M. JAMES, OF JOHNSTOWN, PENNSYLVANIA.

DETONATOR MAGAZINE.

Application filed April 8, 1922. Serial No. 550,745.

To all whom it may concern:

Be it known that I, ARTHUR M. JAMES, a citizen of the United States, residing at Johnstown, in the county of Cambria and 5 State of Pennsylvania, have invented new and useful Improvements in Detonator Magazines, of which the following is a specification.

My present invention has reference to a 10 receptacle for detonator caps, such as are used in conjunction with a fuse in blast firing.

The object of my invention is to produce a receptacle that provides a magazine for detonator caps so that the same can be safely 15 carried and from which they may be delivered one at a time, as required for use.

A further object is to produce a detonator magazine wherein the receptacle shall be in 20 the nature of a cylindrical block having radially disposed openings entering from one of its ends to provide separate compartments for the detonator caps, the compartments being closed by a revolute member provided 25 with a single opening designed, when the member is rotated to register with the several compartments to permit of the removal of the detonators therefrom, and when brought to another position to cover all of 30 the compartments, spring means being provided for latching the closure member in its last mentioned position, said spring means also engaging the said closure when the 35 opening therein is brought opposite the outlet of any of the compartments, holding the closure in such position but permitting the further turning thereof to bring the opening therein to register with the next and with the succeeding compartments.

40 The foregoing, and other objects which will present themselves as the nature of the invention is better understood, may be accomplished by a construction, combination and operative association of parts such as is 45 disclosed by the drawing which accompanies and which forms part of this application.

In the drawing:—

Figure 1 is a plan view of the improvement, the revolute closure being locked to 50 cover all of the compartments.

Figure 2 is a side elevation with the parts arranged as disclosed in Figure 1.

Figure 3 is an approximately central vertical longitudinal sectional view through the 55 improvement, the closure being turned to

bring its opening in registering alignment with one of the pockets in the body.

Figure 4 is a view substantially similar to Figure 1, showing the closure moved to bring the opening thereof in register with one of 60 the compartments.

Figure 5 is a plan view of the magazine with the closure removed.

As disclosed by the drawing, the magazine preferably has its body 1 constructed of a 65 block which is round in cross section. The body 1, from one of its ends is provided with any desired number of spaced series of circumferentially arranged depressions, each of which providing a pocket or receptacle 2 for 70 a detonator cap. In the showing of the drawing, only one series of pockets or receptacles is provided. The pockets or receptacles 2, at the end of the series thereof are spaced a suitable distance away from each 75 other, the said distance being greater than that between the remaining compartments or pockets.

Centrally and pivotally secured on the said end of the body 1 there is a disk-like closure 80 3. The pivot which connects the closure to the body is preferably in the nature of a removable element, and the said closure is, in the present instance, provided with a single opening 4 designed, when the closure is rotated on the body, to register with the several pockets or compartments therein.

The periphery of the disk-like closure is provided with a plurality of equi-distantly spaced substantially V-shaped notches 5, corresponding in number to the pockets or receptacles 2. In addition to this, the closure 3, adjacent to the opening 4 therein is peripherally provided with a substantially rectangular notch 6 of a more determined depth 95 than the V-shaped notches 5.

Let in a longitudinally arranged groove in one side of the body 1 there is a spring rod 7. The rod has one of its ends secured in the said groove, its opposite end projecting a slight distance beyond the closure 3, the said end of the rod being offset to provide a handle portion 8. When the rod is received in the notch 6, the closure 3 is arranged so that the opening 4 therein is disposed over the space in the body 1 between the two end pockets or receptacles 2. The spring rod, when received in the notch will lock the closure from turning on its pivot 9. Thus it will be noted that it is necessary to 110

exert a pressure upon the handle 8 of the rod 7 to bring the same out of the notch. The substantially V-shaped grooves 5 assist the operator in turning the closure on the body

5. 1. As stated, the notches 5 correspond in number to the receptacles or pockets 3, and the spring rod, engaging the first notch 5 on the turning of the disk after the same has been released, as previously referred to, will 10 resist further turning of the closure, so that the detonator in the first compartment may be brought therefrom by the tilting of the magazine. The closure cannot again be accidentally turned, but a determined pressure 15 on the periphery thereof by the operator will cause the spring rod to move out of the referred to notch 5, allowing the closure to further turn until the said rod engages the next notch which brings the opening in 20 the closure in register with the next receptacle or pocket.

It is believed that the foregoing description, when taken in connection with the drawings will fully set forth the construction and advantages of the improvement to those skilled in the art to which such inventions relate. The device complies with the laws of the several States, which make it necessary that miners provide insulating 30 magazines in which the detonators are carried. The device is of an extremely simple nature, may be cheaply manufactured, and the closure for the magazine cannot be accidentally turned to bring the opening therein 35 in register with any of the detonator pockets or compartments.

It is, of course, to be understood that the magazine is not necessarily round in cross section but may be in the nature of a square block that is rounded at the top to provide 40 for the arrangement thereon of the round cover, in which instance the cover is set back a slight distance from the sides of the block to more effectively protect the same against 45 accidental turning.

Having described the invention, I claim:—

1. A detonator magazine including a body

having spaced circumferentially arranged pockets for detonators, a closure pivotally secured to the body and having a single 50 opening therein designed, when turned to certain positions to register with the respective detonator pockets, and when brought to another position, to be brought out of register with any of the compartments, means 55 engaging the closure for locking the same in its last mentioned position, and said means also latching the closure in any of its first mentioned positions.

2. In a detonator magazine, a body having 60 spaced series of annularly arranged pockets for detonators, a pivoted closure for the body having an opening therethrough designed, when turned to certain positions to register with the pockets and when turned 65 to another position to close the pockets, spring means carried by the body engaging the closure for locking the same in its last mentioned position, and said spring means also engaging the closure for latching the 70 same in any of its first mentioned positions.

3. A detonator magazine including a body which is round in cross section and which has a series of annularly arranged spaced depressions entering from one of its ends and 75 providing pockets for detonators, a disk closure pivotally secured on the said end of the body and having an opening therethrough designed, when the closure is turned to certain positions to align with the pockets 80 and when turned to another position to close the pockets, said closure having a peripheral substantially rectangular notch and having 85 V-shaped notches, which latter equal in number the pockets in the magazine, a spring rod on the body of the magazine to be received in the rectangular opening when the closure is in its last mentioned position, and to be received in the V-shaped notches to latch the 90 closure on the body when the opening in the latter has been brought to register with the pockets in the former.

In testimony whereof I affix my signature.

ARTHUR M. JAMES.
